UNITED STATES PATENT OFFICE.

HANS LUNDQUIST, OF CHICAGO, ILLINOIS, ASSIGNOR TO UNITED STATES SPECIALTY CORPORATION, OF CHICAGO, ILLINOIS, A CORPORATION OF ILLINOIS.

LACE-THREADING MACHINE.

Application filed April 23, 1921, Serial No. 463,828. Renewed January 14, 1927.

This invention relates to improvements in lace threading machines which serve for inserting a tape through the mesh of lace-work attached to a garment or not secured thereto.

It is an object of the invention to provide a machine of this character, in which the mechanism for lifting and lowering in alternation one of the two elements to be united, namely the lace and the tape, is controlled electrically.

It is furthermore an object of the invention to provide a machine of this character, in which through one of these elements, the conditions in the electric circuit are intermittently altered, to energize or deenergize in short intervals some electrical means within the circuit and which means in its turn controls the member for moving out of said elements.

The invention also contemplates the provision of a mechanism through which the point of contact between current conducting parts, may be adjusted along one of said parts so as to render the entire mechanism adapted for threading the tape into different kinds of lace.

The invention also contemplates to provide means for facilitating the introduction of the tape or other part to be threaded between gripping shoes and to combine therefore these gripping shoes on a carrier, through the movement of which both of these shoes can be either removed from each other, or brought closer to each other.

The invention also aims at a yielding connection of the gripping shoes to maintain them permanently in a position in which the oscillating movement of one of the elements is assured.

With these and numerous other objects in view an embodiment of the invention is illustrated in the accompanying drawings and described in the following specification.

In the drawing:

Figure 1 is a side elevation of the entire machine.

Figure 2 is a top plan view of the same.

Figure 3 is an end view.

Figure 4 is a sectional view and part elevation, the section being taken on line 4-4 of Figure 2.

Figure 5 is a detail view and part section of the gripping shoes with the contact making device.

Figure 6 is a view of the same parts in a different position, and

Figure 7 is a perspective view of the threading needle.

The entire device is mounted on a base 60 plate 1, which also carries in the embodiment illustrated, a motor 2 connected by a transmission 3, with a positively driven feeding roller or disk 4. This feeding roller is mounted on a shaft 5 which is supported 65 in a frame 6, pivotally carried by a bearing bracket 7. A standard 8 associated with the bearing bracket supports a stationary bar or shaft 9 on which a companion feeding roller 10 is loosely mounted, this companion wheel 70 being in frictional contact with the positively driven wheel 4, so as to be actuated thereby. For the purpose of increasing the friction, one or both of these feeding members may be provided with a knurled or 75 roughened surface.

Another bracket 11 on the base plate supports by the clamp head 12, the needle 13. This needle comprises a straight part 14 and a part which is bent into a loop 15, one end 80 of which is located in a plane different from the straight part 14. This needle is provided practically over its entire length with a groove 17 shown here to have an upright longitudinal rib 18 which divides the groove 85 17 into two parts. The parts terminate in lateral enlargements 19, and the groove may be bridged near its end by a clip 20 beneath which tapes or threads located in this groove may be drawn through. A detachable point 90 21 which is straight and slightly rounded in front, is secured to the needle and projects forwardly.

A pair of gripping shoes 22 and 23 are disposed directly in front of the needle point 95 21, these shoes being preferably semispherical in shape and having on that part which is directed towards the point 21 of the needle, vertical grooves 24 into which the point enters. These shoes therefore may be moved 100 vertically with respect to the needle point 21 and are guided in this vertical movement by the groove 24. Each of the gripping shoes is secured to a yoke or holder 28, and each yoke is associated with one of two 105 pinions 33 and 34, which are in engagement with each other. Upon rotation of one of these yokes to operative or inoperative position (the latter being indicated in dotted lines in Fig. 3) the other one is therefore 110

also moved to the same position. These yokes are connected by springs or resilient yielding tension members 35 which are secured to horizontal parts of the yoke, and 5 which have a tendency to move the two yokes either completely to operative position as shown in full lines in Fig. 3 or completely to inoperative position, but which will prevent the maintenance of either of these yokes 10 between the two terminal positions.

A lever 32 which supports the gripping shoes is pivoted in a standard 36 by the trunnion screws 37. A short arm of this lever which projects beyond the fulcrum has a 15 recess in which a compression spring 38 is located. The upper end of this spring is secured to a screw 39 which extends through a tapped lug of the standard 36 and which may be held in adjusted position by a lock 20 nut. This spring therefore, has a tendency to move the short arm of the lever permanently downwardly, as shown in Fig. 3 to maintain the gripping shoes in their raised position, as indicated in Fig. 5. Another 25 standard 40 which also rises from the base plate 1 has an offset top portion, as indicated in Figs. 1 and 3, the lower horizontal part 41 of this top receiving a set screw 43 through which the downward movement of 30 the holding lever 32 may be adjustably limited, and a similar set screw 44 extends through the upper horizontal portion 42 of this head to limit the swinging movement in 35 upward direction. The front portion of the lever comprises two parallel walls between which the gear segments or pinions 33 and 34 are rotatably mounted.

Lateral arms 45 projecting from the lever 32 form the armature of an electromagnet 40 46 which is secured to the base plate 1. Upon energization of the electromagnet the armature 45 is attracted and the lever 32 will be lowered. When the electromagnet is de-energized however, the forward end thereof 45 will again be forced upwardly owing to the spring 38 at the rear end of the lever.

The bearing frame 6 for the shaft 5 serves for pivotally supporting a yoke 48, Figs. 2 and 4, by means of a screw 49 insulated from the frame 6 by bushings 50 of insulating material. The lateral arms of the yoke 48 support parallel fixed rods 51 on which a slide 52 is guided. A screw spindle 53 is rotatably supported between the 55 lateral arms of the yoke 48 and is held against longitudinal displacement by a collar 54 pinned to the spindle and by the head 55. This spindle extends through a tapped opening of the slide 52, whereby upon rotation 60 of the spindle, a displacement of the slide 52 longitudinally of the yoke may be effected.

An arm 56 projects forwardly from the slide 52, and terminates in a boss 57, with a 65 vertical bore to receive loosely a spindle or

screw 58. The screw 58 is enlarged at its lower end as shown at 59 in Fig. 5 and this portion is slidable within the extension 60 of the boss 57. It is held against rotation within the boss by a pin 61 which projects 70 into a slot of the extension 60, which at the same time serves as a stop to limit the upward movement of the screw 58. Downward movement of the screw 58 within the boss 57 is prevented by a nut 62 which serves 75 for holding the sleeve 59, screw 58 and bearing 57 in a predetermined relation.

A contact shoe 64 is pivotally secured to the projecting end of spindle 58 and has a contact plate 65 which is permanently and 80 yieldingly drawn into engagement with the surface of the needle by a spring 66 secured to an arm of the shoe 64 and anchored at its other end in a lug projecting from the sleeve 59.

The yoke 48 carries on its back a binding post 67 to which the wire 70 is secured. Another conductor 71 is shown to be connected with the winding of the electromagnet 46, and the outleading wire 72 is grounded. 90

The two wires 70 and 71 are connected with opposite poles of a battery or other source of current not shown, and it is obvious therefore, that a circuit will be established from the battery (not shown) through 95 the wire 70, the yoke 48, shoe 64, needle 13, bracket 11, which is also grounded, wire 72, electromagnet 46 and through the wire 71 back to the battery, provided the contact plate 65 is in engagement with a conductive 100 part of the needle. This current, however, is interrupted when the shoe 64 is lifted from the needle.

The operation of the device briefly stated, is as follows: One or more tapes 80 are 105 placed into the groove 17, and formed into loop shape, as defined by the needle. The free end of the tapes may be pulled outwardly sideways through the terminal enlargements 19. The lace through which this tape is to be threaded is indicated at 81, Fig. 5. The end of the lace is placed between the feed rollers 4 and 10 so as to be gripped thereby, and that part of the lace which is located in front of the needle point 115 21, is held by the gripping shoes 22 and 23, which are movable in vertical direction.

When the motor is started the feeding wheels will advance the lace, and strands of the lace will intermittently be pulled through 120 between the shoe 64 and the needle. In these intervals, as indicated in Fig. 6, the shoe rests on the insulating material of the lace, and the circuit to the electromagnet 46 is interrupted to release the armature 45. The spring 38 will immediately force the front end of the carrier 32 for the gripping shoes upwardly, whereby a strand 83, Fig. 5, will be raised above the plane of the needle, and will be placed in this position on 130

the needle. In the continued advance of the lace, strand 82 which before separated the shoe 64 from the needle shank, will have been moved beyond the point of contact with 5 the shoe and a circuit again will be closed through the ground connection, and the electromagnet. The electromagnet will attract its armature 45, lowering the lever 32 and bringing thereby the gripping shoes 22 and 10 23 below the front point of the needle. The strand 84 passing between the gripping shoes towards the needle, will then be placed below the lower surface of this needle.

The effect of this oscillation of the gripping shoes therefore is to bring alternate strands above and below the needle point 21, while the lace is advanced over the entire needle. The tape associated with the needle, is thereby threaded through the lace, 20 so as to alternately overlie the different strands by which the mesh of the lace is formed.

I claim:

1. In an apparatus of the class described, 25 the combination of a needle lace feeding means, and means for arranging different strands of lace in different relation with respect to a thread or tape over which the lace is fed, said arranging means being temporarily separated from the needle by strands of lace advancing over said needle and means laterally of the needle and normally in contact therewith for causing operation of said strand arranging means.

35 2. In an apparatus of the character described, the combination of a threading needle, a gripping device for lace, means for feeding the lace to the needle, an electromagnet and means actuated by the electromagnet for rapidly oscillating said gripping device.

3. In an apparatus of the character described, the combination of the threading needle, means for placing the lace progressively on the needle, a gripping device for the lace, and electrically controlled means for oscillating said gripping device at a speed dependent upon the length of the mesh of the lace.

50 4. In an apparatus of the character described, the combination of a threading needle, means for progressively feeding lace on the needle, a gripping device for the lace located in front of the needle and electrically controlled means for oscillating said gripping device in front of the point of the needle in a predetermined plane, said gripping device being provided with a guiding groove into which the point of the needle enters, and whereby the plane of oscillation of the gripping device is defined.

5. In an apparatus of the character described, the combination of the threading needle, means for progressively feeding lace to the needle, an electromagnet and means

controlled by the electromagnet for alternately raising and lowering lace portions, which advance in direction towards the needle above and below the plane of the needle, said last named means being provided with portions which prevent a lateral deflection of the same, with respect to the point of the needle. 70

6. In an apparatus of the character described, the combination of a needle, a lace feeding means, a pair of cooperating gripping shoes, an electromagnet, means under control of said electromagnet for moving said gripping shoes alternately above and below the point of the needle, and a common carrier for said gripping shoes, said common carrier being the armature of said electromagnet. 75

7. In an apparatus of the character described, the combination of a needle, means for feeding lace to the needle, a pair of gripping shoes located in front of the point of the needle, an electromagnet, means under control of said electromagnet for simultaneously oscillating both of said gripping shoes with respect to said needle point, and means for moving both of said shoes simultaneously to gripping position upon movement of one of the shoes to said position. 85

8. In an apparatus of the character described, the combination of a pair of gripping shoes for the lace, a common carrier for said gripping shoes, separate supports for said shoes mounted on said carrier, and means associated with said supports for producing upon movement of either of said shoes to operative and inoperative position, a similar movement of the other shoe. 95

9. In an apparatus of the character described, the combination with a pair of gripping shoes, a common carrier for the same, an electromagnet, said common carrier being the armature of said electromagnet and adapted to move both of said gripping shoes simultaneously in the same direction, supports between said gripping shoes and said common carrier, and means associated with said supports for preventing the stoppage of either of said shoes at any position different from the operative or completely inoperative position. 105

10. In an apparatus of the character described the combination of a needle, lace feeding means, an electromagnet, an armature, gripping shoes associated with said armature and means under control of the lace for altering the condition of energization of said electromagnet. 120

11. In an apparatus of the character described, the combination of an electromagnet, lace feeding means, an armature for said electromagnet, lace gripping shoes associated with the armature and means for alternately energizing and deenergizing said electromagnet to move said gripping shoes. 125

- 4
12. In an apparatus of the character described, the combination of a needle, lace feeding means, lace gripping shoes movably mounted in front of said needle, electrical means for forcing said gripping shoes in one position with respect to said needle and mechanically controlled means for forcing the gripping shoes into another position with respect to said needle. 40
13. In an apparatus of the character described, the combination of lace feeding means, a needle, lace gripping shoes, electrical and mechanical means for controlling the position of said gripping shoes with respect to said needle, said mechanical means becoming operative upon deenergization of said electrical means. 45
14. In an apparatus of the character described, the combination of a lace feeding means, a needle, means for placing portions of said lace alternately above and below said needle without interrupting the advance movement of the lace, said second means being electrically controlled, a contact shoe 50
- adapted to engage the needle and to be moved from engagement with said needle through the lace traveling on said needle, and electrical connections between said contact shoe and the means for raising and lowering the lace with respect to said needle. 55
15. In an apparatus of the character described, the combination of a needle, lace feeding means, electrically controlled means for placing alternate portions of the lace above and below the needle, a contact shoe 60
- in engagement with the needle, and forming part of the electrical connections for said controlling means, and means for adjusting said contact shoe longitudinally of the needle. 65
16. In an apparatus of the character described, the combination of a needle, electrically controlled means for placing different portions of the lace alternately above and below said needle, a contact shoe engaging said needle and forming a part of the electrical connections to the electrical controlling means, and means for yieldingly urging said contact shoe into engagement with said needle. 70
17. In an apparatus of the character described, the combination of a needle, lace feeding means, lace gripping shoes, electrically controlled means for moving said gripping shoes alternately above and below the level of said needle, and forming a part of the electrical connection to the elements which control the gripping shoes, and means for adjusting the force by which said shoe is pressed against said needle. 75
18. In an apparatus of the character described, the combination of lace feeding means including gripping shoes, a lace needle, electrically controlled means for oscillating the gripping shoes in front of the lace needle, and mechanical means for selectively limiting the end points of the movement of the gripping shoes. 80

In testimony whereof, I affix my signature at 36 W. Randolph St., Chicago, Illinois.

HANS LUNDQUIST.
